George Page of Keene, New Hampshire
Letters Patent

The Schedule referred to in these Letters Patent and making part of the same contains a description in the words of the said George Page himself of his improvement in the common chisel.

It all to inform the present shall come: That I, known by the name of Page of Keene in the County of Cheshire and State of New Hampshire where have invented a new and useful improvement in the common chisel, which improved chisel is called the improved cutting and clearing chisel, and that the following is a full and exact description of the construction and operation of the said machine as invented by me.

The main part of the improved cutting and clearing chisel is made like that of the common chisel. The shank is sometimes made shorter, round, diminishing slightly towards the top but not pointed, and is so made that it may be inserted in an iron socket, and sometimes it is made like that of a common chisel. At the cutting end, it has a main edge & two side edges, or wings. The face is straight like that of a common chisel. The back at the end is bevelled or gradually rounded to an edge, on the back at each of the narrow sides, it has, wing or side edges. These are not more than one sixteenth of an inch thick, and in all cases as thin as may be compatible, with the requisite strength. Their width is, from ~~one~~^{one} ~~five~~^{five} sixteenths of an inch according to the size of the chisel, for soft wood wider than for hard, and they extend up the chisel about half an inch. At the bottom these wings have a sharp cutting edge which trims the sides of the mortise. The edges are formed by beveling inside but most at and near the angles, and by beveling outside but most at and near the corners. These corners are not square but a little rounded. At the upper end the wings are slanted towards the main part of the chisel. They are slightly bevelled on the outside but not to an edge except at the bottom. This chisel is intended to be used principally in mortising machines but may be used as the common chisel is used. — The best cast steel should be used in
